UNITED STATES PATENT OFFICE.

ROBERT D. HAYES, OF NEW HAVEN, CONNECTICUT, ASSIGNOR TO INDEX VISIBLE,
INCORPORATED, OF NEW HAVEN, CONNECTICUT, A CORPORATION OF NEW YORK.

INDEX OR FILE.

1,308,586.

Specification of Letters Patent. Patented July 1, 1919.

Application filed June 8, 1915. Serial No. 32,957.

To all whom it may concern:

Be it known that I, ROBERT D. HAYES, a citizen of the United States, residing in the city and county of New Haven and State of

5 Connecticut, have invented certain new and useful Improvements in Indexes or Files, of which the following is a full, clear, and exact description.

This invention relates to indexes or files, 10 and it has particular reference to a so-called visible index embodying a plurality of record holding members or cards which, in the normal position, are held in overlapped relation so that only the marginal portions 15 of the cards or members are exposed to view. The invention also has special reference to a system of this kind in which each card or other record holding member instead of having the names and other data imprinted 20 or written directly thereon serves as a holder or carrier for a separate record slip or card on which the record matter is written. These record slips are usually of thin paper, and they can be inserted in and removed 25 from the holders without the necessity of removing the latter from their support or supports. In the particular example hereinafter described, each holder is provided with a slip retaining means constructed of 30 celluloid or similar transparent material so that when the slip or insert is placed in the holder the entire face of the former is visible. Thus practically the whole surface of the slip or insert can be utilized for holding 35 record matter which is either visible at all times, or can be made visible by an appropriate manipulation of the holders. My improvements can, however, be used to advantage in other applications or connections.

40 One of the primary objects of the invention is to provide improved means for removably attaching a record slip or insert to a holder.

Another object of the invention is to furnish an index with overlapping holders in which the record slips are retained in place very conveniently and securely between the 45 holders.

A further object which I have in view is 50 the provision of an improved form of holder having a slip retaining pocket so applied thereto as to utilize a large part of the holder surface, and in particular, all of that part of the holder adjacent the side margins.

55 To these and other ends, the invention

consists in the novel features and combinations of parts to be hereinafter described and claimed.

In the accompanying drawing,

Figure 1 is a front elevation of a plurality 60 of overlapped record members embodying my improvements, showing a portion of the supporting strip;

Fig. 2 is a rear view of the parts shown in Fig. 1;

Fig. 3 is an enlarged front view of the two upper holders shown in Fig. 1, with the support omitted;

Fig. 4 is a considerably enlarged section on line 4—4 of Fig. 3;

Fig. 5 is a front view of a single holder or card; and

Fig. 6 is a small diagrammatic view of the pocket forming strip prior to its application to the holder or card.

I have shown my improvements applied to an index of the general type shown in the Fisher Patent No. 1,048,056, dated December 24, 1912, although in the present case the cards or record holders are inverted so 80 as to expose their lower edges. Furthermore, as above intimated, each record holder instead of having the record matter directly imprinted or written thereon is provided with a pocket for a removable record slip 85 or insert. Each card 6 is provided with a pair of tongues 7 to engage a strip-like support 8, as in the patent just mentioned, and these tongues serve as a means for nesting the cards or members together in a predetermined overlapped relation with their lower margins exposed so as to be visible at 90 all times. It will be understood, however, that in some aspects of the invention the method of grouping and supporting the 95 cards or holders is more or less immaterial. In the form shown, each holder 6 is provided with a pocket 9 at its lower exposed margin, which pocket is formed usually of celluloid or similar transparent material. By preference, I take a comparatively narrow strip 10 of celluloid of greater length than the body of the card and attach it to the lower marginal portion of the card in the manner shown in Fig. 5, by folding inwardly and 105 backwardly certain portions 10^a of the strip which overlap the card at the ends of the latter, after which such folded end portions 10^a of the strip are attached to the rear surface of the card by some suitable means, 110

preferably by eyelets 11, one at each extremity of the strip. In the form illustrated, the strip or blank 10 is cut in the shape illustrated in Fig. 6, so that when the 5 end portions 10^a are turned inwardly and backwardly they can be attached to the card by means of the eyelets 11 at points above the pocket on the front face of the card, i. e., above the upper margin of that portion of 10 the strip which traverses the front face of the card. The eyelets 11, or their equivalents, are preferably placed at some distance from the side margins of the card so that they will not tear out, and owing to the fact 15 that they are located above the main part of the pocket, they can be readily set in place by a suitable tool or machine. The lower edge of the strip 10 is folded backwardly and upwardly to form a flange 12 which 20 braces the lower edge of the card 6, and holds the strip firmly in place. In the form shown, the flange 12 is of slightly less width than the card, its ends being cut off at the same angle as the end portions 10^a. 25 The pocket formed by the strip 9 serves to receive a suitable slip or insert which is thereby held on the front face of the card or holder. In the form shown, I employ a slip 13 of comparatively thin paper substantially coextensive with the front face of 30 the card. The lower edge portion of the slip 13 extends down into the pocket 9, while the upper edge of said slip is substantially coincident with the upper edge of the 35 card or holder, as shown in Fig. 4. That portion of the slip 13 which extends into the pocket 9 is readily visible through the transparent material of which the pocket is formed and can, therefore, carry any desired 40 record matter. For example, the lowermost portion of the record slip which is visible through the pocket 9, and which is exposed to view by the overlap of the cards or holders, may carry the name of a person to which 45 other record data on the slip refers. The slip or insert 13 is firmly held in position in its holder when the several holders are assembled together, by reason of the fact 50 that it is prevented from upward displacement by the engagement of its upper edge with the tongues 7 of the card immediately above it, as shown in Figs. 3 and 4. In other words, each slip or insert is held in place between a pocket on what might be termed the 55 free margin of the card and one or more tongues on the next overlapping card.

One of the main advantages of my particular pocket construction resides in the fact that the entire width of the card may 60 be utilized in accommodating the insert or record slip. Again, as above intimated, the record slip can be made substantially coextensive with the card or holder and all portions of said slip are either visible, under 65 normal conditions, or may be made visible

by appropriate manipulation of the cards. The retaining strips 10 extend around the side edges of the card so as to avoid any rough edges or inconvenient projections at those points, and the eyelets are so located 70 that they do not interfere in any way with the ready insertion and removal of the insert. In addition to the record slip or insert, the pocket is adapted to hold any suitable signal element or marker; for example, 75 when the index is used in a bank, and the account of the person whose name appears on the card has been overdrawn, a suitable marker is placed in the pocket, in association with the name, in order to indicate that fact. 80 Usually this is done by using a piece of colored celluloid which is slipped over that portion of the record slip in the pocket so as to obscure the name to a certain extent, and thereby call attention to it without, however, making it illegible.

Without limiting myself to the construction shown, I claim:

1. A record holding member comprising a card, and a transparent pocket forming strip 90 extending along the margin of the card and around and behind the side edges thereof; substantially as described.

2. A record holding member comprising a card, and a pocket forming strip extending 95 horizontally along the margin of the card and around and behind the side edges thereof, and around and behind the horizontal edge thereof; substantially as described.

3. A record holding member comprising a 100 card, and a pocket forming strip extending over the front face of the card along the lower margin thereof, and extending around and behind the card at the side edges thereof, and also at the lower edge thereof; substantially as described.

4. A record holding member comprising a card, a pocket forming strip extending along the margin of the card and around and behind the side edges thereof, and fasteners for securing the extremities of the strip to the card; substantially as described. 110

5. A record holding member comprising a card, a pocket forming strip extending along the margin of the card and around 115 and behind the side edges thereof, and fasteners for securing the extremities of the strip to the card at the rear face of the latter; substantially as described.

6. A record holding member comprising a 120 card, a pocket forming strip of transparent material extending along a horizontal margin of the card and around and behind the side edges thereof, and eyelets for securing the extremities of the strip to the card at the rear face of the latter; substantially as described.

7. A record holding member comprising a card, and a pocket forming strip extending along one margin of the card and having 130

- offset extremities secured to the card at the opposite face of the latter; substantially as described.
8. An index card having a pocket forming strip extending along a horizontal margin thereof and around and behind the side edges of the card, and means for securing the extremities of the strip to the card at the rear face of the latter and at a point offset from the pocket; substantially as described.
9. An index card having a pocket forming strip extending across the front face thereof and around the side edges of the card, and fasteners for securing the extremities of the strip to the rear face of the card at points offset from the pocket on the front face of the card; substantially as described.
10. An index or card having a pocket forming strip extending across the lower edge portion thereof at the front face of the card and around the side edges of the card, and eyelets for securing the extremities of the strip to the card at the rear face thereof, said eyelets located above the upper edge of the pocket; substantially as described.
11. In an index or file, the combination of a support, a plurality of cards mounted flatwise on said support in overlapped relation and having their marginal portions exposed, transparent pocket members extending across the respective cards from side to side and around and behind the side edges of the respective cards, and record slips or inserts in the respective pockets; substantially as described.
12. An index card having a transparent strip extending across the front face thereof and around and back of at least one of its side edges; substantially as described.
13. In an index or file, a card having a pocket on one of its horizontal edges, a slip or insert having one edge located in said pocket, and the opposite edge extending to the opposite edge of the card, and another card overlapping the first card adjacent the last named edge thereof and holding said slip in said pocket; substantially as described.
14. In an index or file, a plurality of record members having tongues nesting them together in overlapped relation, one of said members having a pocket, and a record slip or insert held in place between said pocket and the tongue on the adjacent card; substantially as described.
15. An index card having a transparent strip extending around the lateral edges thereof; substantially as described.
16. In an index or file, the combination of a support, a plurality of cards mounted flatwise on the support in overlapped relation and having their margins exposed, and pocket forming strips extending across the front faces of the respective cards, each of said strips extending around and behind at least one of the side edges of the corresponding card; substantially as described.
17. An index card having a pocket forming strip on the front face thereof extending around and behind at least one of the side edges of the card, that portion of the strip at the rear of the card being offset, and means for securing the offset portion to the card; substantially as described.
18. An index card having a pocket forming strip on the front face thereof provided with an offset extremity secured to the card at the rear face of the latter.
19. An index card having a strip on the front face thereof adjacent one of the horizontal margins with an offset portion extending around to the rear face of the card, and means for securing said offset portion to the rear face of the card.

In witness whereof, I have hereunto set my hand on the 7th day of June, 1915.

ROBERT D. HAYES.
